KNUTE BAKKE, OF WEST ALLIS, WISCONSIN

IRONING BOARD

Application filed November 2, 1929. Serial No. 404,261.

This invention relates to ironing boards which are adapted to be normally housed within wall cabinets when not in use.

While boards of the type that are normally housed in wall cabinets are now in common use they require that a considerable space be left unobstructed immediately in front of the cabinet so that the board may be swung downwardly and still leave a sufficient free area to permit ample working space around the board for the person ironing. In many instances the positioning of the ironing board cabinet by builders is not in conformity with the needs or desires of the housewife who is called upon to make frequent use of the same.

The board of the present invention overcomes the objections noted in the preceding paragraph by being so designed as to permit its being swung in a horizontal plane either toward the wall adjacent one side or the other of the cabinet. In addition to providing an ironing board which may be swung on a vertical axis I have provided simple and effective means whereby the board may readily be anchored in any desired position of lateral adjustment while the same is in position for use. In this manner I insure the sturdiness of a fixed board and simultaneously provide sufficient mobility of the board to permit its being positioned in such a manner as to provide ample working space without requiring the necessity of shifting furniture in the room to provide ample space for accomplishing the desired work.

One object of the present invention is the provision of simple and effective means to permit lateral swinging of the board when the same has been withdrawn from the cabinet in order to allow for the use of a full sized board within a partially restricted space which would otherwise require the use of a smaller board.

Another object is the provision of improved means for releasably retaining the board in any desired position of angular displacement with respect to the cabinet when the board is in position for use.

Other objects and advantages will appear from the following description of an illus-

trative embodiment of the present invention shown in the accompanying drawings.

Figure 1 is a sectional view taken on the line 1—1 of the Fig. 2 showing a board in horizontal position.

Fig. 2 is a plan view of the ironing board taken on the line 2—2 of Fig. 1.

Fig. 3 is a bottom plan view of the rear end of the board showing the supporting means therefore.

Fig. 4 is a fragmentary view of the lower end of the brace member showing the supporting means therefore.

Fig. 5 is a sectional view on the line 5—5 of Fig. 3.

The ironing board shown in the accompanying drawings comprises a board 10 adapted to be swung into a wall cabinet 11 when the same is not in use. The side walls of the cabinet provide suitable mounting means for ways within which the board is guided during the process of withdrawing it for use or replacing it within the cabinet. In the present instance the ways are provided by the application of blocks 12 to the inner faces of the side walls of the cabinet 11. Vertical slots 13 in the blocks 12 form guides for a board supporting member 14. The upper ends of the slots 13 are preferably formed in such a manner as to permit the board to be drawn forwardly a sufficient distance to insure a firm anchorage for the board and retain it in desired position for use. A pair of trunnions 15 are formed on the ends of the member 14. These trunnions 15 are slidable within the slots 13 to permit the board to be swung out of or into the wall cabinet. The board 10 is provided with a reduced end portion 10' which is normally retained between a block 16 and the supporting member 14.

A vertical pivot pin 17 is preferably anchored in the block 16 midway between the extremities thereof. This pin 17 extends through the reduced portion 10' of the board and provides a pivot about which the board may be swung when it has been withdrawn from the cabinet. A pair of bolts 18 are anchored adjacent the ends of the member 16 and extend downwardly through the sup-

porting member 14. The lower extremities of the bolts 18 are adapted to receive thumb nuts 19 which releasably retain the board in any desired position of horizontal angular displacement with respect to the supporting member 14. It will be noted at this time that the bolts 18 are positioned beyond side edges 20 of the cut-away portion 21 of the board. The purpose of so positioning the bolts is to permit the board to swing horizontally on the pin 17 without contacting with the edge of the board. The amount of rotation of the board in either direction is determined by a pair of slanting faces 22 which are formed at the junction of the board 10 and the reduced portion 10' thereof. These faces 22 are adapted to contact with the member 14 to limit the movement of the board with respect to the supporting member 14. The free end of the board 10 is supported by a suitable brace member preferably formed with a pair of legs 23. A hinge 24 which is attached to the board 10 and the upper extremity of the brace serves to anchor the brace and board and provide a rocking connection between the two members. The lower extremities of the legs 23 are rockably connected to a supporting member 25 by means of hinges 26. A pivot pin 27 anchored in a false bottom 28 of the cabinet 11 serves to permit horizontal rotation of the member 25. In accordance with lateral movement of the board 10 the member 28 serves as a load sustaining support for the brace member and board 10.

The board 10 which is normally housed within the cabinet 11 may be withdrawn from the cabinet by pulling the free end thereof forwardly thus drawing the supporting member 14 upwardly along the guide slots 13. As the board reaches a horizontal position it may be drawn forward to permit the trunnions 15 to come to rest in the down-turned extremities of the guide slots 13. When the trunnions are in this position it will readily be seen that the board cannot be accidentally displaced.

When the board has been lowered from the cabinet it may be swung to one side or the other upon the pivots 17 and 27 to the desired position at which time the thumb nuts 19 may be tightened to clamp the reduced portion 10' of the board tightly between the supporting member 14 and a clamping member 16 to thus provide a rigid connection for the board to prevent its being accidentally displaced. As the board is swung laterally it will readily be seen that the braces 23 will swing with the board and simultaneously the brace supporting member 25 will be swung on the pivot 27. In order to insure even greater rigidity of the board I have provided a thumb nut 29 for application to the upper extremity of the pivot pin 27. When the thumb nut 29 is screwed tight-

ly against the top of the brace supporting member 25 it will readily be seen that the same is clamped tightly against the false bottom 28 to insure a firm and rigid support for the braces 23.

When the work of ironing has been completed the board may readily be replaced within the cabinet by loosening the thumb nuts 29 and 19. When this has been accomplished the board may be raised slightly and swung into position directly in front of the open cabinet at which time the free end of the board may be raised to permit the board supporting member 14 to slide downwardly along the slots 13 to permit the board to be swung into the cabinet which houses the same.

It will readily be seen from the foregoing description that a simple and effective means for mounting an ironing board in a wall cabinet has been provided which will permit the board to be swung laterally to any desired position to thus permit the use of a full sized board within limited spaces which would ordinarily require the use of a smaller board which is the source of considerable inconvenience and bother to the user.

While the invention has been described in considerable detail in the foregoing specifications it is understood that various changes may be made in its embodiment without departing from or sacrificing any of the advantages hereinafter claimed.

I claim:

1. The combination of a cabinet having vertical ways in the sides thereof, an ironing board, a pair of transverse bars pivotally connected to one end of said board above and beneath the same, clamp screws coacting with said bars to releasably grip said board therebetween, one of said bars having end trunnions guided in said ways, a brace hingedly connected to said board, a brace support pivotally mounted in the base of said cabinet, and a hinge connection between said brace and brace support.

2. The combination of a cabinet having vertical guide slots in the sides thereof, the upper ends of said guide slots being curved forwardly and downwardly, an ironing board, a pair of transverse bars pivotally connected to one end of said board above and beneath the same, clamp screws coacting with said bars to releasably grip said board therebetween, one of said bars having end trunnions guided in said slots and engageable in the upper down-turned ends thereof to support said board, a brace hingedly connected to said board, a brace support pivotally mounted in the base of said cabinet, and a hinge connection between said brace and brace support.

3. The combination of a cabinet having vertical ways in the sides thereof, an ironing board, a pair of transverse bars pivot-

ally connected to one end of said board above and beneath the same, clamping means connected with the ends of said bars and coacting therewith to grip the board therebetween, one of said bars having end trunnions guided in said ways, a pair of brace members hingedly connected with said board, a bar pivotally mounted in the base of said cabinet, and a hinge connection between each of said brace members and an end of said last named bar.

In witness whereof, I hereunto subscribe my name this 26th day of October, 1929.

KNUTE BAKKE.
